UNITED STATES PATENT OFFICE

NELSON J. RUSSELL, OF CHICAGO, ILLINOIS

FUEL-SAVING DEVICE

Application filed May 16, 1929. Serial No. 363,438.

This invention relates to improvements in fuel saving devices, such as are used to feed preheated air into the fire-box of heating plants, as steam boilers, hot-air furnaces, coal ranges, and the like.

One of the main objects of this invention

is to provide a fuel saving device wherein

the rate of flow of preheated air into the fire-

box is automatically regulated by the tem-

perature in said fire-box.

Another object is to provide such a device

which will automatically start feeding air into the

fire-box upon the starting of the fire and the

rising of the temperature therein, and which

will increase and decrease its rate of flow of

preheated air automatically with the in-

crease and decrease of the temperature in

said fire-box, and will finally stop feeding

air when the fire-box is again cooled down.

A further object is to provide such a device

comprising a casing mountable in a heating

plant and containing partition means to form

a main air heating and expanding chamber

and other partition means extending partly

into said chamber in the first partition means

to provide a compression channel, to cause a deflected and re-

stricted flow of air through said casing and

enable said flow to be regulated by the varia-

tion of heat in said heating plant.

These and other objects and advantages

are attained with this invention, as will be

become apparent from the following descrip-

tion, taken in connection with the accom-

panying drawings, in which

Fig. 1 is a vertical sectional view of the

front part of heating plant, known as a

horizontal flue boiler, having the preferred

form of my invention applied thereto to feed

preheated air into the fire-box.

Fig. 2 is a sectional view taken longitudi-

nally through the device.

Fig. 3 is a cross-sectional view taken on

line 3—3 of Fig. 2.

Fig. 4 shows my invention applied to a

heating plant, known as a hot-air furnace, and therefore comprising a modified form of mounting means.

Fig. 5 is a partial sectional view illustrating the modified form of mounting means.

My improved fuel saving device, which forms the subject matter of the present application, is adapted for use in the various types of heating plants, although the means

for installing or mounting it therein may require variations to better suit the particular type of heating plant in which it is installed, as indicated by the different kinds of mount-

ing means shown in the drawings. The device is preferably installed in the heating plant so as to extend into the fire-box there-

of, and to feed the preheated air therein a

short distance above the burning fuel, about

air when the fire-box is again cooled down, as illustrated.

The improved device illustrated in the drawings comprises a casing 10, which has its body part or main part substantially tu-

bular in shape, and has at its rear end or centrally of the casing, and other partition

means extending partly into said chamber in forming a rear wall, also a tubular neck 12, 70

extending rearwardly from said flange and

providing an air inlet 13 for the entrance of

air into the casing, said neck 12 and flange

11 being preferably integral with the casing.

At its front or free end the casing is pro-

vided with a head or dome 14, which is sub-

stantially semi-spherical and is, preferably

integral with the casing, and has a plurality

of bores or outlet openings 15 therein, for

the discharge of the preheated air.

Partition means or wall means 16 is pro-

vided centrally in the casing, being prefer-

ably channel-shaped or substantially U-

shaped in cross-section, and preferably hav-

ing the ends formed integral with the casing

wall. Its closed part or bight 17 is posi-

tioned adjacent the air inlet 13 in neck 12,

and its flanges or webs 18 extend toward the

front or free end of the casing, thus causing

the current of air to spread and flow adja-

cent the outer wall of the casing, around said webs, as indicated by the arrows in Fig. 2. Said means 16 provides a main or inner heating chamber or expansion chamber 19.

The casing is provided with a cross-wall 5 or cross-partition means 20, which is positioned at the junction of the main tubular part of the casing and its head 14 and serves as a deflecting means to deflect the air which flows forwardly along the outside of webs 10 18. Said wall means 20 is preferably formed integral with the casing wall and forms with head 14 a discharge chamber or outer expansion chamber 21. A slot 22' is provided centrally across this wall, and flanges 15 or bars 23 extend backwardly and flare outwardly from its edges into expansion chamber 19. Said flared flanges or bars 23 on wall 20 provide a compression or contraction channel 22 for compressing and restricting 20 the flow of air therethrough, and they overlap the webs or flanges 18 a distance inwardly thereof; so as to cause the current of air in its flow through inlet 13 and along the outer sides of webs 18 to be deflected 25 by said wall 20 rearwardly between its flanges 23 and said webs 18, into the main or inner heating chamber 19, wherein said air is then highly heated and is restricted or retarded in its flow forwardly therefrom 30 through the contraction channel 22 between the flared flanges 23, into the outer expansion chamber 21 wherefrom it is discharged through the bores or outlet openings 15, as 35 indicated in Fig. 2.

The means for mounting my improved fuel saving device in a heating plant will be adapted to suit the particular occasion, and in Figs. 1 to 3 this mounting means for 40 mounting the device in the fire-box 24 of a horizontal flue boiler 25 comprises flange means or bracket means 26 extending transversely or substantially radially outwards from neck 12, and said bracket means is preferably fastened or secured to the inner 45 side of the door 27 with elements or bolts 28, so as to extend into the fire-box and discharge the preheated air therein a short distance above the burning fuel, about as 50 indicated in Fig. 1. The air enters through the usual openings 29 in door 27, to pass through neck 12 into the casing.

In Figs. 4 and 5 another form of mounting means is shown, which is adapted for 55 mounting my improved device in a hot-air furnace. This mounting means preferably comprises a pipe or tubular member 30 which is attached to the tubular neck 12' of the casing 10'. This attachment or connection is preferably made to be removable and 60 adjustable, as by threading said pipe in said neck, and having a collar 31 threaded on said pipe to press a metal washer 32 and thereby an asbestos washer 33 firmly against 65 the outer side of the wall of the fire-box

34 of the furnace; so that the annular flange or rear wall 11' of the casing will be drawn tightly against the inner side of said fire-box wall, and at the same time the hole provided in the latter and containing said neck 12' will be closed air-tight, and said casing will be held firmly in position in the fire-box to discharge the preheated air through the outlet openings 15' in the head 14' into said fire-box adjacent the burning fuel therein. 70

The tubular member or pipe 30 is made of a length suitable to extend from the neck 12' in wall 34 through the air space in the furnace and through the outer furnace housing or shell 35, to take in the air in its inlet end 30' at the outside of the furnace shell 35. Said pipe is preferably held firmly and air-tight in the shell by means of a collar or ring 36 and a set-screw 37 therein which 80 press a fibre washer 38 tightly against the shell. 85

This casing 10' comprises the channel-shaped partition means 16', and the cross-wall 20' having the flared flanges 23' thereon 90 which extend between the webs 18' of said partition means, the same as in the preceding form above described.

In this improved fuel saving device, constructed in accordance with my invention 95 as disclosed herein, and installed as indicated, the flow of preheated air is self-regulated or the feeding thereof is automatically regulated by the change or variation of the temperature in the fire-box. 100

When the temperature outside of the heating plant is equal to that within the fire-box, or when there is no fire burning therein, then there is no current or flow of air through the device. When the fire in the fire-box is burning and the temperature rises therein, then the air flows through the device, substantially as indicated in Fig. 2. The air entering through air inlet 13 is first deflected by the bight 17 of the channel-shaped means 16, to flow along the outer sides of the webs 18 and have its temperature considerably increased, and is then deflected and reversed in its course by the cross-wall 20 and the flanges 23, entering the main or inner heating chamber 19 wherein it is superheated and expands. The direction of its course is then again reversed, and it again flows forwardly, through the compression channel 22 between the flared flanges 23, 110 being compressed and restricted in its flow therethrough, and therefrom flowing and expanding into the outer expansion chamber 21, whence it flows outward through the outlet openings 15 into the combustion chamber or space above the burning fuel in the fire-box, substantially as indicated in the drawings. This repeated deflected and reverse flow around webs 18 and flanges 23, and through the restriction or compression 115 120 125 130

channel 22, causes the air to flow from this device very slowly while the heat is low in the fire-box and while but little air needs to be added to the burning fuel in the fire-box; however, as the consumption of the fuel and the heat in the fire-box increases, the temperature in the two expansion chambers 19 and 21 also greatly increases, and thereby forces the flow of the preheated air with greater speed out through the outlet openings 15 into the combustion chamber to mingle with the increased volume of burning fuel gases arising from the burning fuel in the fire-box. The rate of flow of air through my improved device is thus increased and decreased automatically by the increase and decrease of the temperature in the fire-box, and in accordance with the requirement of preheated air therein.

20 I am aware that various changes may be made in detail of construction, without departing from the spirit of the invention herein, and I do not purpose limiting the patent granted hereon, except as may be necessitated by the prior patents and art.

What I claim as my invention and desire to secure by Letters Patent is:

1. A fuel saving device in the form of a casing having at one end air inlet means and means for mounting it in a heating plant, baffle means within the casing, extending entirely across the same and having its ends integral therewith and its sides spaced therefrom, partition webs integral with and extending inwardly from the sides of said baffle means and having their sides integral with the casing, to provide a main expansion chamber, a transverse baffle integral with the walls of the casing and spaced from the inner ends of said webs, said transverse baffle having a central slot, diverging webs extending outwardly from the edges of said slot and being in spaced relation with said baffle means and said partition webs, and having their sides integral with the casing, and a rounded head with outlet openings therein to form with said transverse baffle an outer expansion chamber.

2. A fuel saving device consisting of a casting in the form of a casing having all parts integral and including at one end central air inlet means and flange means for mounting it in a heating plant, baffle means within the casing, extending entirely across the same and having its ends integral therewith and its sides spaced therefrom, partition webs integral with and extending inwardly from the sides of said baffle means and having their sides integral with the casing, to provide a main expansion chamber, a transverse baffle integral with the walls of the casing and spaced from the inner ends of said webs, said transverse baffle having a central slot, diverging webs extending outwardly from the edges of said

slot and being in spaced relation with the inner parts of said partition webs, and having their sides integral with the casing, and a rounded head with outlet openings therein extending from said transverse baffle to form therewith an outer expansion chamber 70 for the casing.

In testimony whereof I have signed my name to this specification.
